[57] CLAIM

The ornamental design for an easy opening end closure, as shown and described.

DESCRIPTION

FIG. 1 is a top perspective view of an easy opening end closure, showing my new design;

FIG. 2 is a bottom plan view thereof;

FIG. 3 is a top plan view thereof;

FIG. 4 is a side elevational view thereof, all other side views being identical thereto;

FIG. 5 is a cross sectional view taken along line 5—5 in FIG. 3.
